[57] CLAIM

The ornamental design for a portable clothes hanger, as
shown and described.

DESCRIPTION

FIG. 1 is a front elevational view of a portable clothes
hanger showing my new design, the broken line show-
ing of the front of a clothes dryer being for illustrative
purposes only;

FIG. 2 is a rear elevational view thereof;

FIG. 3 is a side elevational view taken from the right of
FIG. 1;

FIG. 4 is a side elevational view taken from the left of
FIG. 1;

FIG. 5 is a top plan view thereof;

FIG. 6 is a bottom plan view thereof.
